UNITED STATES PATENT OFFICE.

JOHN ABSTERDAM, OF NEW YORK, N. Y.

IMPROVEMENT IN SCREWS.

Specification forming part of Letters Patent No. 58,961, dated October 23, 1866.

To all whom it may concern:

Be it known that I, JOHN ABSTERDAM, of the city, county, and State of New York, have invented a new and useful Improvement in Wood-Screws; and do hereby declare the same is fully described and represented in the following specification and the accompanying drawings, of which—

Figure 1 represents a sectional view of a wooden disk in which are inserted, for comparison, specimens of wood-screws now in use and those of my invention; and Fig. 2, a section at right angles to the same on line *xx*.

The nature of my invention consists in constructing or forming a wood-screw with a boring-point at any desired distance beyond the threaded portion thereof, said point being either conical, pyramidal, or chisel shaped, (like a carpenter's piercer,) for purposes hereinafter explained.

In the drawings, A represents the old square or blunt end screw; B, the more modern or gimlet screw; and C D E F, wood-screws with conical, pyramidal, and chisel shaped boring-points G H I, projecting beyond the threaded portion J, which comprise my invention.

In connecting pieces of wood, or wood and metallic substances, the usual method is to drive with a hammer the old square-end or gimlet wood-screw one-half of its length, or nearly so, into the wood, and by means of a screw-driver the remaining portion, thus cutting or breaking in a portion of the fibers of the wood, and forming a hole equal in diameter to the body of the screw, the broken fibers

invariably clogging up the threads of the portion of the screw so driven, destroying the function or proper action of the screw because of its form, which is proved by the fact of the screw dropping out after some jarring or vibration of the wood.

In using my improved wood-screw, the usual method of driving the same (and from which carpenters and others seldom deviate) may be continued with advantage, for in driving my wood-screw the conical or tapering point will not break, cut, or drive the fibers of the wood before it, or clog up the thread, but will, from its peculiar form, (in being driven through,) only spread the fibers apart in its advance, leaving the wood unbroken to embrace the thread of the screw, thus rendering it stable against vibration or jar of the wood; besides, my wood-screw, combining the property of piercer and screw, will require but one-half the manual power to insert the same in the wood as compared with those in present use.

What I claim as new, and desire to secure by Letters Patent, is—

The above-described wood-screw with the plain cylindrical portion between the point and the threaded portion, substantially as and for the purposes set forth.

In testimony whereof I have hereunto set my signature.

JOHN ABSTERDAM.
